CLOSED FEED SYSTEM FOR STEAMSHIPS

Filed Sept. 27, 1927

Inventor
James Sim.

By William C. Linton,
Attorney.

UNITED STATES PATENT OFFICE.

JAMES SIM, OF CATHCART, GLASGOW, SCOTLAND, ASSIGNOR TO G. & J. WEIR, LIMITED,
OF CATHCART, GLASGOW, SCOTLAND.

CLOSED FEED SYSTEM FOR STEAMSHIPS.

Application filed September 27, 1927, Serial No. 222,407, and in Great Britain November 10, 1926.

This invention consists in an improved closed feed system for steamships.

When a ship is fitted with a closed feed system for the main driving units, it is very desirable to have the harbour auxiliaries working on a closed feed system in harbour. This is particularly desirable in warships, which in general spend the major portion of their lifetime in harbour. The present invention allows this desideratum to be obtained.

The invention consists in a feed system for a steamship power plant, including both main and auxiliary steam motors. The arrangement is such that the system is maintained closed whether both the main and auxiliary steam motors are in operation (as when the ship is at sea) or when only the auxiliary steam motor (or motors) is in operation (as when the ship is in harbour). The system comprises an arrangement and combination of elements which, with the functioning thereof, will be explained and made clear by the following description and the accompanying diagrammatic drawing.

The invention will be defined in the annexed claim.

a is an auxiliary engine, e. g. a steam turbine which is always running whether the ship is at sea or in port. *b* is the condenser for *a*. *c* is a tank arranged below the condenser *b*. The water of condensation flows from the condenser into this tank.

A water-extraction pump *z* of the centrifugal type withdraws feed water from the tank *c* and—when the ship is in harbour—delivers it under a pressure of about 20 pounds per square inch above atmosphere along the pipe *n* direct to a harbour feed pump *f* which delivers it into the main feed water conduit *v* and thence to one (or more) of the (main) boilers *m*. A small float *d* in the tank *c* controls a supplementary feed valve *e* on a pipe *h* which leads from a fresh water tank *k* to the condenser *b* and serves to admit supplementary feed water to the system in accordance with the water level in the tank *c*.

The control and action of the arrangement when the ship is in harbour are as follows:

Owing to the relative size of the harbour auxiliaries and the main boilers, the latter may be regarded as of large water capacity so

that, under varying loads—i. e. harbour loads—there will be no appreciable, or at least very little, variation in the boiler water level. The variation in the quantity of water delivered by the feed pump will therefore be small; and this variation will be sufficiently met by the float-controlled supplementary feed valve.

A pipe *o* is provided connecting the pipe *n* with the main feed water conduit on the suction side of the main feed pump *w*. A hand-controlled valve *t* is provided on this pipe. Valves *r* and *s* are provided on the pipe *n* on the suction and discharge sides respectively of the pump *f*, or one or other only of these valves may be fitted. A valve *u* is placed on the conduit *v* on the discharge side of the pump *w*.

When the ship is running at sea, the valves *r* and *s* (or one of them) are shut, and the harbour feed pump is stopped: the valves *t* and *u* are open and the main feed pump run. The feed water therefore from the tank *c* is delivered by the water extraction pump into the main feed water conduit *v* on the suction side of the main feed pump. When the ship is in harbour, the valves *r* and *s* are open and the valves *t* and *u* shut.

It will be seen that, whether the ship is at sea or in port, the de-aerated condensate from the auxiliaries which exhaust into the condenser *b* passes in a closed feed system to the boilers.

Having thus described my invention, what I claim as new and desire to secure by Letters Patent is:—

A feed system for a steamship power plant, the system comprising a steam generator, an auxiliary engine, a condenser for the said auxiliary engine, a tank arranged below the said condenser, means whereby the condensate flows from the said condenser into the said tank, a main feed conduit, a water-extraction pump of the centrifugal type, acting to withdraw feed water from the said tank and deliver it into and along the said main feed conduit, a main feed pump on the said main feed conduit, a hand controlled valve on the discharge of the said feed pump, a harbour feed pump intended for use when the ship is in harbour, a pipe connecting the discharge of the said water-extraction pump

with the suction of the said harbour feed pump and a hand-controlled valve on this pipe, a pipe connecting the discharge of the said harbour feed pump with the said main feed conduit beyond the valve hereinbefore mentioned as being on the discharge of the said boiler feed pump and a hand-controlled

valve on this pipe, a pipe connecting the discharge of said water-extraction pump with the said main feed conduit on the suction side of the said boiler feed pump and a hand-controlled valve on this pipe.

I hereby sign my name to this specification.

JAMES SIM.
